SCRATCH BRUSHING APPARATUS FOR
CLEANING PORTIONS OF CIRCULAR
ARTICLES

Jerome R. Marcus, Chicago, and Lawrence B. Walter, Elmhurst, Ill., assignors to Western Electric Company, Incorporated, New York, N. Y., a corporation of New York

Application July 3, 1946, Serial No. 681,214

3 Claims. (Cl. 15—21)

1

This invention relates to scratch brushing apparatus and more particularly to a rotary brush type of apparatus for cleaning portions of the resistance elements of circular potentiometer units.

One type of potentiometer unit is made by winding insulated wire on flat strips of insulation to form resistance elements known as potentiometer cards which then must be scratch-brushed along one edge to remove the insulation from the wire. The flat resistance elements, together with insulation strips and slip ring strips, are bent into annular shape and cemented together in annular grooves in one side of a housing so that the cleaned edges of the resistance elements and the edges of the slip rings project from the face of the housing in concentric spaced relation to each other and are adapted to be engaged by sliding contact members. In cementing and assembling the parts together, some of the cement used may get on the cleaned edges of the resistance elements and it is necessary to reclean the projecting edges of the resistance elements without damaging or defacing the slip rings thereon.

It is an object of this invention to provide a simple and effective apparatus for cleaning arcuate articles.

In one embodiment of the invention, there is provided a plurality of stations at each of which there is a plate for supporting a circular potentiometer unit and a spindle extending upwardly from the plate about which the potentiometer unit may be manually rotated. Grooves are formed in each of the plates concentric with the spindles for receiving the edges of the annular resistance elements, which comprise coated wire wound on thin strips of insulation and which project from the face of the potentiometer unit. At each station, a rotary scratch brush extends upwardly into a recess in the underside of each plate, which recess intersects a groove in the upper side of the supporting plate to form a slot through which the rotary scratch brush may engage the wire on the edge of the resistance elements and clean foreign matter therefrom. The brushes and the slots through which they engage the edges of the resistance elements are spaced relative to the spindles at the various stations so that the brushes engage a different one of the resistance elements of the potentiometer unit at the different stations whereby a potentiometer unit may be positioned successively on each of the spindles and rotated through one or more revolutions to clean the resistance wires on the

2

edge of each of the potentiometer cards thereon.

A more complete understanding of the invention may be had by reference to the following detailed description thereof and the accompanying drawings illustrating a preferred embodiment of the invention wherein

Fig. 1 is a plan view of the apparatus showing four stations at each of which a potentiometer unit may be partially cleaned and showing, in dotted lines, the rotary scratch brushes and the means for driving them;

Fig. 2 is a vertical sectional view of a portion of the apparatus, with parts broken away, taken on the line 2—2 of Fig. 1 in the direction of the arrows and showing a potentiometer unit in dot and dash lines at each of the stations of the apparatus;

Figs. 3, 4, 5 and 6 are vertical sectional views through portions of the apparatus taken on the lines 3—3, 4—4, 5—5 and 6—6, respectively, of Fig. 1 in the direction of the arrows and showing a portion of a potentiometer unit on the supporting member and the rotary brushes engaging the edges of different potentiometer cards at each of the different stations;

Fig. 7 is an enlarged fragmentary vertical sectional view through the potentiometer unit showing a potentiometer card, insulating strips, and a slip ring mounted in an annular groove of the potentiometer unit;

Fig. 8 is an enlarged fragmentary plan view of one station of the apparatus shown in Fig. 1, showing the means for supporting and positioning a potentiometer unit thereon;

Fig. 9 is a vertical sectional view of a portion of the apparatus taken on the line 9—9 of Fig. 8 in the direction of the arrows, showing the potentiometer unit supporting and positioning means and the rotary scratch brush and showing a potentiometer unit in dot and dash lines;

Fig. 10 is a vertical sectional view of a portion of the apparatus taken on the line 10—10 of Fig. 1 and showing a potentiometer unit in position thereon;

Fig. 11 is an enlarged face view of a portion of the potentiometer unit; and

Fig. 12 is an enlarged fragmentary view of a potentiometer card showing the resistance wire wound thereon.

Referring to the drawings, the apparatus shown is for cleaning a circular potentiometer unit of the type illustrated in Figs. 3, 7, 10, 11 and 12. The potentiometer unit 15 comprises a cylindrical housing 16 having a central aperture 17 therethrough and a plurality of concentric an-

nular grooves 20, 21, 22 and 23 formed in one side thereof in which are mounted the resistance elements or potentiometer cards 25, 26, 27 and 28, respectively. As shown particularly in Figs. 7 and 12, each resistance element comprises a coated wire 30 wound on a flat strip or card of insulation 31 with the turns of wire in spaced relation to each other. The resistance elements are processed in a scratch brushing operation to remove the insulation from the wire along one edge of the potentiometer cards prior to their assembly in the unit. The resistance elements 25, 26, 27 and 28 are mounted in the grooves of the potentiometer unit with the cleaned edges thereof projecting a predetermined distance from the surface of the potentiometer unit and with insulating cards 35 and 36 positioned on each side thereof. Metallic slip rings 39 mounted in each of the grooves of the potentiometer unit extend beyond the face of the potentiometer unit, each with the edge thereof in a predetermined spaced relation to the edge of the potentiometer card associated therewith and the rings 39 are held in position in the grooves by corrugated metal spacers 40 (Figs. 7 and 11) interposed between the slip rings 39 and the adjacent insulating cards 36.

Metallic contact members (not shown) are adapted to engage the windings 30 of the various resistance units 25, 26, 27 and 28 and the respective slip rings 39 associated therewith. In the assembling of these parts, a cement is used to secure the resistance elements, the insulating cards 35 and 36, the slips rings 39 and the spacers 40 in proper position in the grooves in the potentiometer unit. Because some of the cement may inadvertently be applied on the cleaned edges of the potentiometer cards, it is necessary to re-clean the edges thereof so that the sliding contact members may make metallic contact between each of the various points of the resistance elements at the extending ends of the cards and the slip rings 39 associated therewith.

The cleaning apparatus comprises a housing 44, in the forward portion of which there is provided a plurality of stations 45, 46, 47 and 48, and at which stations the resistance elements 25, 26, 27 and 28, respectively, are adapted to be cleaned. A plate 49 (Figs. 1 and 10) secured to end walls 50 and 51 of the housing 44, forms a top for the rear portion of the apparatus adjacent the stations 45-48. From the end walls 50 and 51 of the housing 44 extend horizontal attaching flanges 52 and 53 (Figs. 1 and 2), which engage the underneath side of a table or bench top 54, and are secured thereto by bolts 55 so that the top of the apparatus fits in a recess in the table 54 and is substantially flush therewith. Formed integral with, as by welding, and extending between the end walls 50 and 51 of the housing are a rear wall 56 (Fig. 1), a bottom wall 57 (Fig. 10), an oblique front wall 58 and a vertical front wall 59. A horizontal shelf 60 is formed by an angle member 61 welded to the oblique wall 58 (Fig. 10) and the end walls 50 and 51 (Fig. 2). Extending rearwardly from the upper portion of the front wall 59 are a plurality of horizontal supports or plates 64, 65, 66, 67 and 68 (Figs. 1, 2 and 10), the plates 64 and 68 being attached to the end walls 50 and 51, respectively. At their rear ends, the supporting plates 65, 66 and 67 are supported by vertically extending integrally formed supporting members 73-73 (Fig. 2), which project upwardly from and are welded to the shelf 60.

Mounted on each of the plates 65, 66, 67 and 68 is a bracket 70, apertured to receive a pivot pin 71. The ends of the pivot pins 71 extend beyond the brackets 70 and engage in apertures 72-72 (Fig. 8) in lugs 74-74 formed on the ends of a plurality of adjustable supporting plates 75, 76, 77 and 78 at the stations 45, 46, 47 and 48, respectively. The supporting plates 75, 76, 77 and 78, at one end, are pivotally supported on the pivot pins 71 (Figs. 8 and 9) and at their opposite ends are provided with apertures 81 forming shoulders 82, which are engageable with the heads 83 of machine screws 84. The machine screws 84 are adjustably mounted in threaded apertures 85 in the supporting members 64, 65, 66 and 67 and support each of the adjustable plate members in an adjusted position. Apertures 87 having shoulders 88 are provided in the supporting plates 75, 76, 77 and 78 adjacent the apertures 81 and are adapted to receive the heads 89 of clamping screws 90, which engage threaded apertures 91 in the supporting members 64, 65, 66 and 67.

Each of the supporting plates 75, 76, 77 and 78 is provided with a positioning spindle or rod 92, which is secured in an aperture 93 in the plate and extends upwardly from the upper surface 94 of the plates for positioning a potentiometer unit in a predetermined position on the supporting plate, as indicated in dot and dash lines in Figs. 2, 8 and 9. Formed in the upper side of the plates 75, 76, 77 and 78 are annular grooves 95, 96, 97 and 98, respectively, of various diameters positioned concentrically with the positioning spindles 92 to receive the projecting edges of the resistance elements 25, 26, 27 and 28, respectively, of the potentiometer unit when the potentiometer unit is moved successively from one station to the other to clean successive resistance elements. The slip ring 39 associated with the resistance element being cleaned is adapted to engage the upper surface 94 of the supporting plate to support the element being cleaned in a predetermined vertical relation to the supporting plate. At each station, (Figs. 3, 4, 5 and 6) the upper side of the supporting plate is also formed with annular depressions or grooves 99-99 to provide clearance for the three sets of resistance elements and slip rings not involved in the cleaning operation. Arcuate recesses 100, 101, 102 and 103 are formed in the underneath side of the plates 75, 76, 77 and 78, respectively, and intersect the annular grooves 95, 96, 97 and 98, respectively, to provide slots 105, 106, 107 and 108 in the plates.

Rotary scratch brushes 110, 111, 112 and 113 fit into the recesses 100, 101, 102 and 103, respectively, of the supporting plates 75, 76, 77 and 78 and engage the respective resistance elements 25, 26, 27 and 28 when the potentiometer unit is positioned at the stations 45, 46, 47 and 48, respectively. The axes of the scratch brushes 110 to 113 and the centerline of the notches 100 to 103 are located at various distances from the axes of the spindles 92, which distances correspond to the radial distances between the resistance elements 25-28 and the axis of the potentiometer unit.

The adjustable supporting plates 75-78 are adjusted by means of the supporting and clamping screws 84 and 90 to the proper position relative to the brushes so that when a potentiometer unit is applied to the supporting plate, the peripheral surface of the rotary brushes will engage 75 the edge of the resistance element and clean a

predetermined portion of the wire wound thereon. It will be apparent that when a potentiometer unit is positioned at any of the stations, as shown in Figs. 3-6, it will be supported on the surface 94 of the supporting plate by the slip ring 39 associated with the resistance element being cleaned and the slip ring controls the extent to which the resistance element projects into the slot in the supporting plate and limits the extent of the engagement of the resistance element with the rotary scratch brush associated therewith. The position of the rotary scratch brush is so related to the potentiometer unit at each station during the cleaning operation that it only engages the edge of the resistance element being cleaned and does not contact any other part of the potentiometer unit.

The rotary brushes 110, 111, 112 and 113 are secured to the ends of horizontal shafts 115, 116, 117 and 118, respectively, which are mounted in suitable bearings in bearing blocks 120—120 secured to the shelf 60. The shafts 115 and 118 have keyed to one end thereof pulleys 124 and 125, respectively, and the shafts 116 and 117 have keyed thereto double pulleys 126 and 127, respectively. The shafts 115—116 and the shafts 117—118 are operatively connected together by belts 129 and 130, respectively, and the shafts 116 and 117 are connected to a motor pulley 131 by belts 132 and 133, respectively. The motor pulley 131 is mounted on a shaft 134 of a reversible driving motor 135 suitably mounted in the housing 44. The direction of the motor is controlled by forward and reverse control switches 137 and 138, respectively, as indicated in Fig. 1. By reversing the rotation of the brushes when cleaning the resistance elements, a better cleaning effect is obtained and the bristles of the brushes are straightened.

An exhaust system is provided to carry away the material removed from the potentiometer during the cleaning operation and comprises individual housings or casings 140 (Figs. 2 and 10) surrounding the rotary scratch brushes and connected to and forming a part of an exhaust conduit 141 mounted on the shelf 60 and extending through the end wall 51 (Fig. 2). The exhaust conduit 141 may be connected to any suitable exhaust system. The upper open ends of the exhaust housings 140 are spaced from the supporting plates 75—78 and cooperate with telescoping tubular members 142 secured to the under side of the supporting plates.

After a potentiometer unit has been completely assembled and it is desired to clean the edges of the resistance elements therein, an operator may place the potentiometer unit over the spindle 92 at one of the stations as, for example, 45, and move the potentiometer unit downwardly into engagement with the supporting plate 75. The potentiometer unit is then supported on the surface 94 of plate 75 by the slip ring 39 associated with the resistance element 25. The edge of the resistance element 25 is then properly positioned vertically in the groove 95 and contacts the peripheral surface of the rotating scratch brush 110 through the slot 105. The rotating scratch brush 110 will remove the cement and other foreign material from the portion of wires of the resistance element 25 from which the insulation has been removed, and by rotating the potentiometer unit about the spindle 92 through one or more complete revolutions with the brush rotating in one direction and then rotate the potentiometer unit with the brush rotating in the

reverse direction, the operator may effect the cleaning of the contact surface of the resistance element 25. The potentiometer unit may then be removed from station 45 and applied to station 5 46 in a similar manner and rotated through one or more revolutions. At station 46, the potentiometer unit will be supported by the slip ring 39 associated with the resistance element 26 and the resistance element 26 will be positioned in the annular groove 96 and will contact the rotating scratch brush 111 through the slot 106 and, as the resistance element 26 is rotated, the lower edge thereof will be cleaned. Upon the completion of the cleaning of the resistance element 26, 10 the potentiometer unit may be withdrawn from station 46 and applied to station 47, where the resistance element 27 may be cleaned in a cleaning operation similar to that described for cleaning the resistance elements 25 and 26, upon the completion of which the final resistance element 28 may be cleaned in a similar manner by applying the unit to station 48 and rotating it through one or more complete revolutions.

What is claimed is:

1. An apparatus for cleaning arcuate resistance elements of an electrical device comprising a member for supporting said electrical device, means on the supporting member for positioning the electrical device for rotation about its axis, said supporting member having annular grooves therein for receiving the arcuate resistance elements projecting from the electrical device and a recess therein intersecting one of said grooves to form a slot through which a portion of a resistance element is accessible, a rotary scratch brush projecting into the recess to engage and clean a portion of the resistance element accessible through the slot, and means for rotating said brush.

2. An apparatus for cleaning the edge of arcuate resistance elements of a circular potentiometer unit comprising a plate for supporting a potentiometer unit thereon and having an annular groove on one side thereof for receiving the arcuate resistance element projecting from the potentiometer unit and a recess on the opposite side thereof intersecting said groove to form an arcuate slot through which a portion of the resistance element is accessible, a post on said supporting plate concentric with said groove for positioning a circular potentiometer unit for rotation about its axis and with the arcuate resistance element in said groove, a scratch brush mounted for rotation about a fixed axis and projecting into the recess to engage and clean a portion of the resistance element accessible through the slot, and means for rotating said brush.

3. An apparatus for cleaning arcuate resistance elements of an electrical device comprising a frame, a supporting member pivotally connected at one end to the frame for supporting an electrical device thereon and having a circular groove in the upper portion thereof for receiving the edge portion of a circular resistance element of the electrical device and having a recess intersecting the groove to form an arcuate slot in the supporting member through which a portion of the resistance element is accessible, a spindle mounted on said supporting member in concentric relation to the annular groove therein for positioning the electrical device for rotation about its axis on the supporting member with a portion of an arcuate resistance element of the electrical device in the slot in the supporting member, a rotatable scratch brush mounted on the frame and engage-

7
able with a portion of the resistance element through the slot in the supporting member; means for rotating the scratch brush, and a threaded member adjustably mounted on said frame and member adjustably mounted on said frame and engageable with said supporting member to limit the pivotal movement thereof in one direction, and a second threaded member adjustably mounted on said frame and engageable with said supporting member to limit the pivotal movement thereof in the opposite direction, said members 10 being operable to lock said supporting member in an adjusted position relative to said scratch brush.
